James D. McDonald, Los Angeles, Calif.

Application June 29, 1946, Serial No. 131,201

Term of patent 14 years

(Cl. D26—13)

To all whom it may concern:

Be it known that I, James D. McDonald, a citizen of the United States, residing at Los Angeles, in the county of Los Angeles and State of California, have invented a new, original, and ornamental Design for a Switch Escutcheon, of which the following is a specification, reference being had to the accompanying drawing, forming part thereof.

In the drawing

Fig. 1 is a front elevation of a switch escutcheon, showing my new design;

Fig. 2 is a side elevation of the switch escutcheon; and

Fig. 3 is an end elevation of the switch escutcheon.

I claim:

The ornamental design for a switch escutcheon, as shown.

JAMES D. McDONALD.
